Primary Examiner — Susan Bennett Hattan*Assistant Examiner* — Rebecca Tsehay(74) *Attorney, Agent, or Firm* — Gurr Brande & Spendlove, PLLC; Robert A. Gurr(57) **CLAIM**

The ornamental design for a cartridge for electronic cigarette liquid, as shown and described.

DESCRIPTION

FIG. 1 is a front perspective view of the cartridge for electronic cigarette liquid;

FIG. 2 is a front elevation view of the cartridge for electronic cigarette liquid;

FIG. 3 is a back elevation view of the cartridge for electronic cigarette liquid;

FIG. 4 is a left side elevation view of the cartridge for electronic cigarette liquid;

FIG. 5 is a right side elevation view of the cartridge for electronic cigarette liquid;

FIG. 6 is a top plan view of the cartridge for electronic cigarette liquid; and,

FIG. 7 is a bottom plan view of the cartridge for electronic cigarette liquid.

The broken lines shown in the drawings are for the purpose of illustrating portions of the article that form no part of the claimed design.
